UNITED STATES PATENT OFFICE.

JOHN WESLEY SANDY, OF CREAL SPRINGS, ILLINOIS.

WAGON-BODY HOIST.

SPECIFICATION forming part of Letters Patent No. 471,900, dated March 29, 1892.

Application filed February 5, 1892. Serial No. 420,424. (No model.)

To all whom it may concern.

Be it known that I, JOHN WESLEY SANDY, a citizen of the United States, and a resident of Creal Springs, in the county of Williamson and

5 State of Illinois, have invented certain new and useful Improvements in Devices for Hoisting or Removing Wagon-Bodies; and I do hereby declare that the following is a full, clear, and exact description of the invention, 10 which will enable others skilled in the art to which it appertains to make and use the same, reference being had to the accompanying drawings, which form a part of this specification.

15 My invention relates to improvements in devices for hoisting or removing wagon-bodies from wagon-beds, the object being to provide a simple, economical, and efficient construction of the same.

20 The invention consists in the novel construction and combination of parts hereinafter fully described, and specifically pointed out in the claim.

In the accompanying drawings, Figure 1 is 25 a view showing my improved device in place in a wagon-shed ready for use. Fig. 2 is a view, on an enlarged scale, of the windlass and its frame.

In the said drawings, the reference-numeral 30 1 designates the windlass-frame consisting of two side bars connected together at or near their centers by a cross-bar 2. In the upper ends of the side bars is journaled a windlass 4, having secured thereto at each end disks 35 5, one of which is provided with a series of peripheral ratchet-teeth 6, with which engage a pawl 7, pivoted to said frame, whereby backward movement of the windlass is prevented. The windlass is also provided with a pin 8, to 40 which the hoisting-rope is connected, as hereinafter described, and with a crank or handle 9. The lower ends of the side bars of the frame are provided with apertures 10, through 45 12, by which the frame is secured to an upright or vertical joist of a barn or wagon-shed, as will hereinafter appear.

Connected with the ceiling joist or roof of the shed is a double sheave 13, and at a short 50 distance therefrom is a single sheave 14.

These sheaves are connected to the roof by swivel connections, so that they will adjust themselves automatically to the position occupied by the windlass.

The numeral 15 denotes the hoisting rope 55 or cord.

The operation is as follows: The sheaves are secured to the roof at a distance apart corresponding with the wagon-body. The windlass-frame is then connected with one of the 60 uprights, the lower ends of the side bars embracing two of the sides thereof, as seen in Fig. 1, with the edges of the cross-piece lying or bearing against one of the other sides. The rod 12 is then passed through the apertures 65 10, bearing against the side opposite to that with which the cross-piece engages. One end of the hoisting-rope is now secured to the wagon-body and passed up over the sheave 14, from whence it passes to the upper sheave 70 13, and from thence downward to the windlass, where it is wound around the pin 8, and from thence carried up around to the lower sheave 13 to the wagon-body, with which it is secured. By now turning the windlass by 75 means of the crank the wagon-body will be lifted or hoisted, the ratchet-teeth and pawl preventing any backward movement of the windlass.

Having thus described my invention, what 80 I claim is—

In a wagon-body-hoisting device, the combination of the side bars, each provided with a series of apertures, the intermediate cross-bar, the windlass having a pin, and end disks, 85 one of which is provided with ratchet-teeth, the pivoted pawl, the removable and adjustable rod passing through apertures in the lower ends of said frame, the double and single sheaves adapted to be connected with a 90 roof or other support, and the hoisting rope or cord, substantially as described.

In testimony that I claim the foregoing as my own I have hereunto affixed my signature in presence of two witnesses.

JOHN WESLEY SANDY.

Witnesses:
